UNITED STATES PATENT OFFICE.

FRANK REED, OF DOWAGIAC, MICHIGAN.

CYLINDRICAL WALL STRUCTURE.

1,198,662.

Specification of Letters Patent. Patented Sept. 19, 1916.

Application filed December 8, 1915. Serial No. 34,640.

To all whom it may concern:

Be it known that I, FRANK REED, a citizen of the United States, residing at Dowagiac, county of Cass, State of Michigan, have invented certain new and useful Improvements in Cylindrical Wall Structures, of which the following is a specification.

This invention relates to improvements in cylindrical wall structures.

10 My improved cylindrical wall structure is especially designed by me for silo structures and I have illustrated the same embodied in such a structure.

The main objects of my invention are: 15 First, to provide an improved silo of the block or stave type in which the blocks are effectively interlocked. Second, to provide in a silo an improved structure providing a series of uniform door openings.

20 Further objects, and objects relating to structural details, will definitely appear from the detailed description to follow.

I accomplish the objects of my invention by the devices and means described in the 25 following specification.

The invention is clearly defined and pointed out in the claims.

A structure which is a preferred embodiment of my invention is clearly illustrated 30 in the accompanying drawing, forming a part of this specification, in which:

Figure I is a front elevation of a silo structure embodying the features of my invention. Fig. II is an enlarged detail vertical section on a line corresponding to line 2—2 of Fig. I. Fig. III is a front elevation of one of the door casing blocks. Fig. IV is a front elevation of one of the wall blocks. Fig. V is a detail horizontal section on a 40 line corresponding to line 5—5 of Fig. I, showing the form of the abutting edges of the blocks.

In the drawing similar reference characters refer to similar parts throughout the 45 several views, and the sectional views are taken looking in the direction of the little arrows at the ends of the section lines.

Referring to the drawings, 1 represents the concrete foundation of a silo. The silo 50 is preferably started and finished with half blocks 2.

The wall blocks 3 are provided with tapered end projections 4 centrally disposed, the bases of the projections being spaced 55 from the edges of the blocks to provide shoulders 5 at each side. One edge and one

end, including the interlock projections, are outwardly curved, as at 6. The opposite edge and end are inwardly curved or grooved at 7, the grooves and curved edges being complementary. These wall blocks are curved in cross section and are laid in courses, as illustrated, with their interlock projections interlocking, the ends of the projections abutting the shoulders of abutting pairs of blocks of the adjacent courses. These end projections are of substantial size and length so that the hoops 8 may be disposed over the same, as shown, binding both ends of the blocks. 70

The blocks are laid to provide door openings and in alternate courses are laid the frame-like door casing blocks 9. These blocks have door openings 10 and the spaces 11 between the blocks also constitute door 75 openings. The blocks 9 are shouldered at each end at 12 to coact with the ends of the abutting blocks of the adjacent courses. The casing blocks are provided with a curved edge 6 and a grooved edge 7 adapted to coact with the edges of the abutting blocks in the courses in which they are laid. The curved edges and grooves extend onto the shouldered projections 12 and onto the ends of the blocks, as shown in Fig. III, to coact 80 with the curved edges and grooves of the interlock projections, and the shoulders of abutting blocks. The hoops 8 are arranged across the ends of the casing blocks. The doors 13 are secured by the bars 14. The details of securing the doors form no part of my present invention. With the blocks thus formed and arranged they may be conveniently laid in courses and are interlocked and effectively supported by the hoops. 85

Having thus described my invention, what I claim as new and desire to secure by Letters Patent, is:

1. A cylindrical wall structure of the class described, comprising wall blocks having tapered centrally disposed interlock projections at their ends, the bases of the projections being spaced from the edges of the blocks providing shoulders at each side thereof, said blocks being laid in courses 100 with the interlock projections of adjacent courses interlocking, the ends of the interlock projections abutting the shoulders of abutting pairs of adjacent courses, said blocks being curved in cross section and 105 having one edge and end including the interlock projection thereof curved outwardly,

the other edge and end including the interlock projection thereof being grooved to receive the outwardly curved edges of the blocks abutting, frame-like door casing 5 blocks laid in alternate courses of said wall; said casing blocks having door openings therein, the spaces between said casing blocks also constituting door openings, the ends of said casing blocks being shouldered 10 to coact with the ends of the abutting blocks of adjacent courses, the abutting edges of the said casing blocks being curved and grooved to complement the curved and grooved edges of the abutting blocks, and 15 encircling hoops disposed across the interlock projections of said courses of blocks and the ends of said casing blocks.

2. A cylindrical wall structure of the class described, comprising wall blocks having 20 tapered centrally disposed interlock projections at their ends, the bases of the projections being spaced from the edges of the blocks providing shoulders at each side

thereof, said blocks being laid in courses with the interlock projections of adjacent 25 courses interlocking, the ends of the interlock projections abutting the shoulders of abutting pairs of adjacent courses, frame-like door casing blocks laid in alternate courses of said wall, said casing blocks having 30 door openings therein, the spaces between said casing blocks also constituting door openings, the ends of said casing blocks being shouldered to coact with the ends of the abutting blocks of adjacent courses, and 35 encircling hoops disposed across the interlock projections of said courses of blocks and the ends of said casing blocks.

In witness whereof, I have hereunto set my hand and seal in the presence of two 40 witnesses.

FRANK REED. [l.s.]
